UNITED STATES PATENT OFFICE.

GRiffin S. ACKLEY, OF BUFFALO, NEW YORK, ASSIGNOR TO G. S. ACKLEY & COMPANY.

BRAKE MECHANISM.

1,158,764.

Specification of Letters Patent.

Patented Nov. 2, 1915.

Application filed January 15, 1912. Serial No. 671,234.

To all whom it may concern:

Be it known that I, GRIFFIN S. ACKLEY, a citizen of the United States, residing at Buffalo, in the county of Erie and State of New York, have invented a new and useful Improvement in Brake Mechanisms, of which the following is a specification.

This invention relates to winding mechanisms for brake chains for cars and is applicable more particularly to that type of brake mechanism in which a hand actuated operating shaft is employed and the winding drum for the brake chain is arranged adjacent to this shaft above the floor of the car and is so constructed that the brake chain may be wound thereon in either direction, but the invention is not necessarily limited to brake mechanisms of this type.

One object of the invention is to provide the winding drum with an auxiliary chain which is secured thereto and engages the brake chain for limiting the releasing movement of the brake chain and the drum. The auxiliary chain is adapted to be wound upon the drum as the latter rotates to unwind the brake chain and is adjustably connected to the brake chain, so that the extent to which the brake chain will unwind when the drum is released for releasing the brakes can be limited as desired. The auxiliary chain also serves to reinforce the portion of the brake chain adjacent to the drum, so that if this portion of the brake chain should break or become disconnected from the drum the auxiliary chain will secure the brake chain to the drum and enable the brakes to be applied.

Further objects of the invention are to provide simple and compact operative connections between the hand operated arm or wheel and the winding drum, which can be easily and firmly secured in position in the supporting frame or casing, and to provide the operating arm or wheel with a hinged handle which when not in use can be turned inwardly out of the way, and, when desired, can be readily turned outwardly to a position in which it can be easily grasped by the operator for turning the operating arm or wheel to apply the brakes.

In the accompanying drawings: Figure 1 is a front elevation of a brake mechanism embodying the invention. Fig. 2 is a sectional side elevation thereof. Fig. 3 is a

fragmentary sectional elevation in line 3—3, Fig. 2. Fig. 4 is a similar view showing the position of the parts when the drum has been released. Fig. 5 is a fragmentary sectional elevation on line 5—5, Fig. 1, on an enlarged scale. Fig. 6 is a similar sectional elevation showing a modified form of construction. Fig. 7 is a fragmentary front elevation on an enlarged scale of the wheel showing the handle in its inturned position. Fig. 8 is a sectional side elevation on line 8—8, Fig. 7. Fig. 9 is a similar fragmentary view showing the handle turned outwardly.

Like reference characters refer to like parts in the several figures.

The brake mechanism shown in the drawings is of the general type of that described and claimed in Letters Patent of the United States No. 1,002,531, issued to me Sept. 5, 1911, in which a reversible winding drum is employed which is capable of winding the brake chain in either direction and which is journaled in a supporting frame or casing, above the floor of the car adjacent to a winding shaft which is operated by a hand operated arm or wheel on the front of the casing. It will be understood, however, that the present invention is not limited to a brake mechanism of this particular type, but is applicable to other and different types and constructions of brake mechanisms.

In the construction, shown, A represents the frame or casing, B the reversible winding drum which is journaled therein, and C the brake chain which is attached by a pin *c* to that portion of the periphery of the drum which is of greatest radius, so as to wind thereon in either direction. The chain C passes downwardly from the drum through an opening in the floor of the car and over a pulley D to a brake rod or other part which is connected to the brakes. The drum B is provided at one end with a ratchet E, engaged by a pawl *e* which normally prevents the drum from unwinding and is released by a foot lever *e'* to permit the drum to unwind to release the brakes. At its opposite end the drum B has gear teeth *f* which mesh with the teeth of a pinion F which is operatively connected with a hand operated arm or wheel G for rotating the drum to apply the brakes. All of these parts may be of any usual or suitable construction.

H represents an auxiliary chain which is secured at one end to the winding drum B, preferably by the pin c which secures the brake chain C thereto, and at its opposite end is provided with a snap hook h or other connection which is adapted to detachably engage in the links of the brake chain at some little distance from the drum. When the drum B is rotated to wind the brake chain thereon for applying the brakes, the auxiliary chain hangs slack or loose as shown in Figs. 2 and 3. When the drum is released it quickly rotates in an opposite direction unwinding the brake chain and releasing the brakes under the action of the usual brake releasing springs, (not shown). This unwinding movement of the drum serves to wind the auxiliary chain H thereon, thus taking up the slack in this chain until it becomes taut and prevents further releasing movement of the brake chain, as shown in Fig. 4. The snap hook h which connects the end of the auxiliary chain to the brake chain, permits the end of the auxiliary chain to be easily secured in any of the different links of the brake chain, so that the extent to which the brake chain can unwind when the drum is released may be limited, as desired. By attaching the auxiliary chain to the drum, rather than to a stationary part on the frame or casing, this chain serves not only to limit the releasing movement of the brake chain, but also limits the unwinding movement of the drum when released. This prevents the drum from rotating to unwind the brake chain therefrom any more than is necessary to release the brakes, so that there will be no unnecessary amount of slack in the brake chain when unwound, and thus reduces the amount of rotation of the drum which would otherwise be required for taking up slack in the brake chain when the brake is again applied, and enables the brakes to be more quickly and easily applied. The auxiliary chain further reinforces the brake chain, so that if the latter should break above its point of attachment to the auxiliary chain, it will not become disconnected from the winding drum nor drop down, but will be held by the auxiliary chain and the latter can then be wound upon the drum for drawing up the brake chain and applying the brakes. When the auxiliary chain is used in a construction, such as the one shown in the drawings in which a horizontal winding drum is used, it supports the weight of the brake chain depending from the drum and thus prevents the further unwinding movement of the drum which the weight of the chain would otherwise produce and holds the brake chain sufficiently taut so that the brakes can be quickly applied. The use of the auxiliary chain, however, is not limited to this particular style of construction, but it can be

used to advantage with winding drums of other constructions arranged in different positions.

The operative connections between the wheel G and the pinion F are constructed as follows:—I represents an operating shaft which is arranged parallel with the axis of the drum and has a reduced end i which is journaled in a bearing portion i' in the rear wall of the frame or casing A. Adjacent to its end i, the shaft is provided with a square or rectangular portion i² which is adapted to fit in a correspondingly shaped opening in the pinion F, so that the pinion and shaft turn together. At its opposite or forward end I has a rounded journal portion i³ upon which is journaled a bearing sleeve K which projects inwardly from the operating wheel G, and in the construction shown in Figs. 1, 2 and 5 is formed integrally with the wheel. The front end of the sleeve K is closed by a cap k which forms an oil retaining chamber at the front end of the shaft I.

In the construction shown in Figs. 1, 2 and 5, the sleeve K is provided at its rear end with ratchet teeth k' and a clutch member L is mounted on the square portion of the shaft I having teeth l which are adapted to engage the teeth k'. The clutch member L is movable endwise of the shaft and is held in yielding engagement with the sleeve K by a coiled spring l' which is inserted between the clutch member and the pinion F. The clutch permits the operating wheel to turn freely on the shaft I in one direction but locks the shaft and wheel, so that they rotate together when the wheel is turned in an opposite direction.

The sleeve K is journaled in an opening in the front wall of the supporting frame or casing and for this purpose a circular bearing bushing M is preferably provided which is arranged in the opening between the sleeve and the casing and has an outwardly extending flange m which is adapted to engage the front face of the supporting frame or casing around the opening. The operating handle has an annular shoulder m' which bears against the front end of the bearing bushing M and retains the latter in place in the casing, and the sleeve K in turn is held in place in the casing by a collar N which surrounds the inner end of the sleeve within the casing and bears against the inner face of the front wall thereof. This collar may be secured to the sleeve by the set screw n, or in any other suitable manner. The sleeve K thus forms a journal support for the front end of the operating shaft I and the construction forms a very strong, simple and compact connection between the operating wheel and the pinion. The parts can be easily and quickly assembled and secured in operative position in the

frame or casing and can be as easily removed therefrom, if desired.

In fig. 6, a modified form of connection is shown in which a detachable sleeve O is employed which is secured to the operating wheel G by a set screw o and is provided at its ends with oppositely disposed ratchet teeth o' and o^2 and a clutch member P is arranged on the operating shaft and has oppositely disposed end teeth p and p' which are adapted to engage the teeth o' and o^2 , respectively, when the corresponding ends of the sleeve and clutch member are arranged adjacent to each other. This construction is adapted more particularly for use in brake mechanisms having a reversible winding drum upon which the brake chain can be wound in either direction. By reversing the clutch member P and the sleeve 20 O, the mechanism can be easily changed, so that the operating wheel must be turned in an opposite direction for applying the brakes. The brake mechanism can thus be shifted from a right handed mechanism to 25 a left handed mechanism or vice versa with little trouble.

In the construction shown, a hand wheel is provided for winding the drum to apply the brakes, but the operative connections 30 above described between the wheel and the winding drum can be employed with equal facility in connection with any other suitable construction of hand operated winding means.

To facilitate the turning of the hand wheel or other operating arm for applying the brakes, a handle R is provided which is secured thereto in such a manner that it can be turned to project outwardly therefrom in position where it can be readily grasped by the operator for turning the wheel to apply the brakes, and when not in use can be turned inwardly to a position where it will lie within the rim substantially in the plane of the wheel or operating arm and will be out of the way. In the construction shown, the handle R is hinged to the rim of the hand wheel in the following manner:—

The wheel rim is provided on its inner face with spaced lugs or ears r between which the base of the handle is inserted and to which it is pivoted by a pin r' which extends through the base and is secured at 55 its opposite ends in these lugs. The base of the handle is provided with notches r^2 and r^3 and a spring detent r^4 mounted in the wheel rim is adapted to engage in these notches for holding the handle respectively 60 in its outturned and inturned positions. A stop r^5 on the base is adapted to engage the inner edge of the wheel rim for limiting the inward movement of the handle. The handle will thus normally remain in either position to which it is turned, but can be easily

moved from one position to the other when desired. This construction forms a simple means for hinging the handle to the operating wheel, but any other suitable connecting means may be employed which permit the 70 handle to be moved into and out of its operative position.

I claim as my invention:

1. In a brake mechanism, the combination of a rotatable chain winding drum having a 75 connection for the brake chain and corresponding peripheral winding portions which extend about said drum in opposite directions from said chain connection and which converge from said connection toward the 80 axis of rotation of the drum, a brake chain attached to said chain connection, and an auxiliary chain attached at one end to the same chain connection to which said brake chain is attached and at its opposite end to 85 said brake chain, said chains in the normal released position of the brake extending from their connection to said drum in opposite directions in said peripheral winding portions of said drum, whereby when the 90 drum is rotated one chain will be wound thereon as the other chain is unwound therefrom, said auxiliary chain being wound on the drum during the last part of the unwinding of the brake chain therefrom and thereby checking the momentum of the drum and limiting the unwinding of the brake chain, substantially as set forth. 95

2. In a brake mechanism, the combination of a frame, a chain winding drum, a shaft 100 which is operatively connected with said drum and is journaled at one end in said frame, an operating member arranged on the opposite end of said shaft, and means for connecting said operating member to 105 said shaft so that they will turn together, said operating member being journaled in said frame and forming a support for the end of said shaft, substantially as set forth.

3. In a brake mechanism, the combination of a frame, a chain winding drum, a shaft 110 which is operatively connected with said drum and is journaled at one end in said frame, an operating member journaled on the opposite end of said shaft, and a clutch member on said shaft adapted to engage said operating member for connecting the latter to said shaft, said operating member being journaled in said frame and forming a support for the end of said shaft, substantially as set forth. 115

4. In a brake mechanism, the combination of a frame, a chain winding drum, a shaft which is journaled at one end in said frame, an operating member journaled on the opposite end of said shaft, a pinion secured on said shaft intermediate of its ends and geared to said drum, a clutch member mounted on said shaft and movable endwise thereof, a spring interposed between said 120 125 130

pinion and said clutch member for holding the latter in yielding engagement with said operating member and a journal bearing in said frame for said operating member, substantially as set forth.

5. In a brake mechanism, the combination of a rotatable winding drum, a brake chain attached thereto, an auxiliary chain attached at one end to said drum, and means for connecting the other end of said auxiliary chain to said brake chain at any portion thereof, said chains in the normal released position of the drum extending around said drum in opposite directions from their points of attachment whereby one chain is wound on the drum when the other chain is unwound therefrom.
- 10 15 6. In a brake mechanism, the combination

of a rotatable winding drum, a brake chain attached thereto, an auxiliary chain attached at one end to said drum, and a connecting member at the other end of said auxiliary chain and adapted to engage with any of the links of said brake chain for connecting said auxiliary chain thereto, said chains in the normal released position of the drum extending around said drum in opposite directions from their points of attachment whereby one chain is wound on the drum when the other chain is unwound therefrom.

20 25 30 Witness my hand this 11th day of January, 1912.

GRiffin S. ACKLEY.
